UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

STATIC-POTENTIAL-CONTROLLING APPARATUS.

Original application filed June 14, 1919, Serial No. 304,308. Divided and this application filed February 23, 1923. Serial No. 620,790.

To all whom it may concern:

Be it known that I, ROBERT M. GILSON, a citizen of the United States, residing at Pittsburgh, in the county of Allegheny and 5 State of Pennsylvania, have invented certain new and useful Improvements in Static-Potential-Controlling Apparatus, of which the following is a specification.

My invention relates to static potential controlling apparatus, and particularly to apparatus for controlling the potential applied to current-consuming devices which are known to be limited as to life. Such devices may, for example, be electric lamps, 10 tungar rectifiers, or other devices comprising heated filaments, although I do not wish to be limited to any particular character of current-consuming device.

One object of my invention is the provision of means having no contacts or other moving parts, for placing a reserve current-consuming device in service when a device which has previously been in service ceases to function.

25 The present application is a division of my copending application Serial No. 304,308, for static potential controlling apparatus, filed June 14, 1919, now Patent No. 1,449,987, issued on the 27th day of March 30 1923.

I will describe one form of apparatus embodying my invention, and will then point out the novel features thereof in claims.

The accompanying drawing is a diagrammatic view showing one form of apparatus embodying my invention.

Referring to this drawing, the reference character T' designates a transformer, the secondary of which is connected with a current-consuming device L' , which, as here shown, is an incandescent lamp. This lamp L' will be hereinafter referred to as the "main" lamp. The primary of the transformer T' is supplied with alternating current by suitable means, such as the secondary of a transformer T^2 whose primary is connected with a source of alternating current which is not shown in the drawing. Suitable means are provided for limiting the amount of current supplied to transformer T' , this means as here shown being a reactance R interposed between the two transformers. A reserve current-consuming de-

vice L^2 , also in the form of an incandescent lamp, is connected across the terminals of 55 the primary of transformer T' .

The parts of the apparatus shown in Fig. 1 may be so proportioned that while lamp L' is burning at normal voltage the voltage applied to the reserve lamp L^2 is considerably below normal, but that when lamp L' burns out, the voltage applied to lamp L^2 will be increased to the normal value so that this lamp will then burn at normal brilliancy. As an example, I have found that 60 this result may be attained by proportioning the parts as follows:

I will assume that each lamp L' and L^2 is of the tungsten filament type and that these lamps are of about two candle power, 70 taking .2 ampere at 10 volts, lamps of this type and size being the ones which are customarily used for semaphore lighting in railway signaling. The resistance of each lamp when hot, is, of course 50 ohms. If 75 the transformer T' is made with a 1:2 ratio, and if the voltage of the secondary is 10 volts, it follows that when lamp L' is burning the current flowing in the primary will be .4 ampere. The potential across the primary of transformer T' is then, of course, 80 5 volts, so that the voltage applied to lamp L^2 , is then half of the normal value. While lamp L^2 is supplied with half of its normal voltage, its resistance will be about 75% of 85 its resistance when hot; that is, about 37.5 ohms. The current flowing in lamp L^2 is, therefore, $\frac{5}{37.5}$ which equals .13 ampere. I

will, furthermore, assume that the exciting 90 current for transformer T' is 20% of the local current, that is, .08 ampere at .4 power factor, and that this exciting current increases in proportion to the applied voltage. It will be found by computation, or by the 95 construction of a vector diagram, that the total current flowing in reactance R is then about .56 ampere. I will assume that the power factor of the reactance R is .1 and that the value of this reactance is about 23 100 ohms. If the potential at the secondary of transformer T^2 is 15 volts, the result will be a potential of 10 volts across lamp L' , while this lamp is burning.

When lamp L' burns out, there will be 105 a potential of 15 volts applied to a cir-

cuit composed of the reactance R in series with an impedance composed of lamp L^2 and the primary of transformer T' in multiple. Assuming that lamp L^2 now burns at 10 volts, its resistance will be 50 ohms at unity power factor. The impedance of the primary of transformer T' is

$$\frac{5}{.08}$$

10

which equals 62.5 ohms at .4 power factor. To combine these two impedances in multiple it is necessary to determine the admittance of each branch. The admittance of the lamp L^2 is

$$\frac{1}{50} = .02$$

The admittance of the primary of transformer T' is

$$\frac{1}{62.5} = .016$$

By computation or by vector diagram it will be found that the combined admittance of these two impedances is .03, at an angle of 29 degrees. The combined impedance of lamp L^2 and the primary of transformer T' is therefore

$$\frac{1}{.03} = 33.3 \text{ ohms}$$

this impedance also being at an angle of 29 degrees. To this must be added the impedance of the coil R (23 ohms at .1 power factor). The total impedance in the circuit will then be found to be about 50 ohms. The current flowing in the circuit is therefore

$$\frac{15}{50} = .3 \text{ ampere}$$

It follows that the potential across lamp L^2 and across the primary of transformer T' is $.03 \times 33.3 = 10$ volts, which is the desired voltage at this lamp after lamp L' burns out.

Although in describing in detail the operation and structure of the apparatus embodying my invention, I have referred to the current-consuming devices as incandescent lamps, and have so illustrated them in the drawings, it is understood that I do not limit myself to devices of this particular

type. Any current-consuming device or devices may be substituted for the lamps shown in the drawing.

Although I have herein shown and described only one form and arrangement of apparatus embodying my invention, it is understood that various changes and modifications may be made therein within the scope of the appended claims without departing from the spirit and scope of my invention.

Having thus described my invention, what I claim is:

1. Static potential controlling apparatus comprising a transformer, a main current-consuming device connected with the secondary thereof, a reserve current-consuming device connected across the primary of said transformer, and means for limiting the amount of current flowing to the primary of said transformer.

2. Static potential controlling apparatus comprising a transformer, a main current-consuming device connected with the secondary thereof, a reserve current-consuming device connected across the primary of said transformer, and a reactance connected in series with the primary of said transformer.

3. Static potential controlling apparatus comprising a step-up transformer, a main current-consuming device connected with the secondary thereof, a reserve current-consuming device connected across the primary of said transformer, and means for limiting the amount of current flowing in the primary of said transformer.

4. Static potential controlling apparatus comprising a transformer, a main current-consuming device connected with the secondary thereof, a reserve current-consuming device connected across the primary of said transformer, and a reactance connected in series with the primary of said transformer, the parts being so proportioned that when the main device is consuming current the potential applied thereto is the normal operating value and the potential applied to the reserve device is considerably below the normal operating value, but that when the main device is not consuming current the potential applied to the reserve device rises to the normal operating value of the device.

In testimony whereof I affix my signature.

ROBERT M. GILSON.
